UNITED STATES PATENT OFFICE.

ROBERT W. JEMISON, OF MACON, GEORGIA.

BOOKKEEPER'S STOOL.

SPECIFICATION forming part of Letters Patent No. 722,585, dated March 10, 1903.

Application filed December 6, 1902. Serial No. 134,195. (No model.)

To all whom it may concern:

Be it known that I, ROBERT W. JEMISON, a citizen of the United States, residing at Ma-
5 con, in the county of Bibb and State of Georgia, have invented new and useful Improvements in Bookkeepers' Stools, of which the following is a specification.

This invention relates to what I shall for convenience term a "bookkeeper's stool," al-
10 though it will be evident from the following description that it may be used with advan-
tage by other workers; and the primary ob-
ject of the invention is to provide a simple
15 and effective device of this character, includ-
ing a stool and a supporting-frame therefor
having means for sustaining the stool for trav-
eling movement, whereby said stool can be
readily shifted from place to place along the
20 front of a desk or the like without the neces-
sity of the user leaving the same.

The invention includes other objects and
advantages, which, with the foregoing, will
be set forth at length in the following descrip-
tion, while the novelty of the invention will
25 form the basis of the claims succeeding said
description.

Said invention is clearly represented in the
accompanying drawings, forming a part of
this specification, and in which—

30 Figure 1 is a side elevation of a bookkeep-
er's stool including my invention in one sim-
ple and convenient embodiment thereof. Fig.
2 is a front elevation of the said stool. Fig. 3
is a plan view of the same.

35 Like characters of reference indicate like
parts throughout the several views.

The improved device embodies in its con-
struction a frame for supporting a stool for
traveling movement, and said frame is illus-
40 trated as consisting in the present case of the
duplicate end columns or uprights 2, which
may be of any suitable material—such, for
example, as castings. The said columns or
uprights 2 terminate at their lower ends in
45 legs 3, provided with ball-bearing casters 4,
so that the supporting-frame and the parts
carried thereby can be readily moved from
place to place. The columns or uprights 2
are united at their front and rear by the rails
50 5, located one above the other and constitut-
ing tracks for receiving the wheels of the
traveling stool-carriage. These rails 5 may

be made from any suitable material—for ex-
ample, tubing or piping. The ends of the
rails are threaded to fit the nuts 6, the bodies 55
of the nuts being cylindrical and being adapt-
ed to lie within circular depressions or pock-
ets formed in the columns or uprights 2 and
held therein by the clips 7, screwed or other-
wise attached to said columns, it being seen 60
that the clips where they engage the bodies
of the nuts are curved to agree therewith, so
that said nuts can be readily turned in order
to properly connect the end columns or up-
rights. The outer sides of the nuts have 65
squared extensions 8, by which said nuts may
be turned by a wrench of other suitable tool.

The stool is denoted by 9, and it is pro-
vided with a seat of some suitable kind from
the body of which the screw 10 depends, such 70
screw passing through a nut 11 upon the up-
per side of the approximately rectangular
carriage 12. The said carriage 12 is pro-
vided near its opposite ends with axles 13;
provided at their outer ends with wheels 14 75
of some suitable kind peripherally grooved
to receive the superposed rails 5. The pe-
ripheries or tires of the wheels 14 are pref-
erably of rubber or are otherwise cush-
ioned, so that the wheels as they travel along 80
the rails can do so noiselessly and without
jar to the occupant of the stool or chair 9.
The lower rails in each case might be con-
sidered the supporting ones, while the upper
rails prevent tilting movement of the car- 85
riage as the same rolls back and forth upon
the lower rails.

By means of the screw 10, depending from
the body of the stool 9 and extending through
the relatively fixed nut 11, said stool can be 90
readily raised or lowered, as occasion may
require.

The device is adapted for advantageous use
by bookkeepers, draftsmen, and others who
use high or stand-up desks or tables to accom-
plish their work, for the reason that the stool
while it is occupied by the user can be read-
ily moved from place to place along the sup-
porting-rails 5 without the necessity of such
occupant leaving the stool, by virtue of which 95
much time is saved in certain kinds of work—
for example, in posting books.

I mount under the lower rails upon each
side of the frame the rods 15 in parallelism

with the rails, the opposite ends of said rods being threaded to fit the nuts 16, the cylindrical bodies of which are mounted for turning movement in the lower ends of the ar- 5 cuate slots 17, formed in the end columns 2, and said nuts, like the ones hereinbefore described, have squared extensions 18, by which they can be readily operated in order to secure the rods in place. Truss-brackets are 10 shown at 19, they being of approximately X shape and separated at suitable distance, their lower branches being equipped with sleeves to receive the rods 15, while the upper branches are concaved to receive the lower 15 track-rails.

Upon the rods 15, between the lower branches of the braces 19, are fitted the sleeves of truss-brackets 20, which depend from said rods and are grooved at their lower ends to 20 receive the truss-rods 21. The ends of the truss-rods extend through the columns or up- rights 2 and are threaded to receive the nuts 22. The outer ends of the truss-rods, it will be seen, are deflected slightly upward, so 25 that when the nuts 22 thereof are turned onto the same an upward stress is applied to the truss-rod which is transmitted to the rod 15, and thereby to the lower rails 5, through the intermediate truss-brackets 20 and braces 19, 30 so as to prevent said lower rails from springing or buckling between their ends.

Upon the inner side of the frame or that side thereof which is next a desk or its equivalent is a foot-rest 23, consisting of a bar co- 35 extensive with the rails 5 and terminating in the inwardly-extending arms 24, which fit against the inner faces of the columns or up- rights 2. Bolts 25 extend through said arms 24 and also through vertically-elongated slots 40 26 in the columns 2 in order to provide for the vertical adjustment of the foot-rest. The rods 15 are united near their opposite ends by the braces or cross-pieces 27, provided at their extremities with sleeves to receive the 45 said rails.

The frame, consisting of the columns or up- rights 2, united by the rails 5 and rods 15, which latter are braced in the manner indicated, is a thoroughly stable structure, pos- 50 sessing means for preventing the buckling or bending of the rails upon which the stool-carriage 12 is directly mounted.

The different parts hereinbefore described may be made of any suitable material. For 55 example, as previously stated, I may make the columns or uprights 2 of castings and the rails 5 and rods 15 of tubing.

The frame is preferably connected with the desk or table, and the means shown for this 60 purpose I will now describe.

To the braces 27, substantially centrally thereof, I pivot the outwardly-extending links 28, to the outer ends of which are like- 65 wise connected similar links 29, pivoted to a desk, table, or other support at their outer ends, such table or its equivalent being indicated diagrammatically and only in Fig. 3.

When the device is not in use, the frame can be pushed under a desk, and when it is de- 7c sired to employ the same it can be readily with- drawn therefrom. When the frame is under the desk, it is out of the way and it can be em- 75 ployed as a foot-rest. As the frame is con- nected with the desk, it can be readily moved from place to place therewith, and as it is equipped with casters it can be moved along a tiled, wood, linoleum, or carpeted floor without possibly injuring same. As the frame carries the track upon which the stool or chair 9 is mounted, it will be seen that such stool 80 or chair can be moved along the front of the desk without the necessity of mounting the same upon a track upon the floor, as in such case the track disfigures the floor and inter- 85 feres with the usual arrangements of a mer- cantile or other establishment.

By means of the device a user occupying the stool or chair 9 and with his feet upon the rest 23 can by pressure upon said rest readily propel himself from place to place 90 along the desk and with a very slight effort and without the necessity of using the hands for this purpose, so that the hands are left free and can be employed in posting books or for checking from one book to another 95 or accomplishing other work requiring long desk-room, and as the wheels of the stool-carriage are rubber-tired such carriage trav- 100 els noiselessly. The stool or chair 9 not only has a rotary movement, but it is adjustable vertically to any desired height. The de- 105 vice, it will therefore be understood, is sim- ple and effective, thoroughly strong, and ad- vantageous for the purposes intended.

I do not limit the invention to the exact 105 construction hereinbefore described, for any variations may be adopted within the scope of my claims.

It is evident that more than one of the trav- 110 eling stool-carriages can be mounted upon the track in order to accommodate several persons, this being advantageous where a num- 115 ber of persons have to work at the same desk—for example, in railroad-offices.

Having described my invention, what I 115 claim is—

1. In a device of the class specified, a frame consisting of columns, rails located one above the other uniting the columns at their front and rear, rods also uniting the columns below 120 the lower rails, braces between the lower rails and rods, truss-rods below said other rods, the outer portions of which are deflected upward and extend through the columns and termi- 125 nate in threads having nuts upon the outside of the column, and truss-brackets between the truss-rods and the first-mentioned rods.

2. In a device of the class specified, a frame, consisting of columns, rails located one above the other uniting the columns at their front 130 and rear, rods also uniting the columns below the lower rails, braces between the lower rails and rods, truss-rods below said other rods, the outer portions of which are deflected upward

and extend through the columns and terminate in threads having nuts upon the outside of the column, and truss-brackets between the truss-rods and the first-mentioned rods, 5 combined with a carriage provided with a stool and peripherally-grooved wheels to receive and travel upon said rails.

3. In a device of the class specified, a frame consisting of end columns, rails located one 10 above the other uniting the end columns at their front and rear, rods also united with the columns below the lower rails, braces between the lower rails and rods, truss-rods below said other rods, the outer portions of which are deflected upward and extend through the columns and are provided at their ends with threads, nuts upon the outer sides of the columns upon said threads, truss-brackets between the truss-rods and said first-mentioned 15 rods, and braces uniting the first-mentioned rods.

4. In a device of the class specified, a frame consisting of end columns, rails connecting said columns at their front and rear, rods also 20 connected with the columns and located below said rails, braces between said rails and rods, truss-rods below said other rods, the outer portions of which are deflected upward and extend through said columns and terminate in threads, nuts upon the outside of the 25 columns upon said threads, and truss-brackets between the truss-rods and the other rods.

5. In a device of the class specified, a frame

consisting of end columns having casters to rest upon a foundation, rails one above the other uniting the end columns at their front and rear, rods also united with the columns below the lower rails, braces between the lower rails and rods, truss-rods below the other rods, the outer portions of which are deflected upward and extend through the columns and terminate in threads, nuts on the outside of the columns upon said threads, truss-brackets between the truss-rods and said other rods, combined with a carriage having peripherally-grooved wheels to receive said rails and a nut, and a stool having a depending screw to enter said last-mentioned nut. 40

6. In a device of the class specified, a frame consisting of end columns, rails uniting said 45 columns at their front and rear, rods also united with the columns and located below the rails, braces between the rails and rods, truss-rods below the other rods, truss-brackets between said truss-rods and said other rods, the outer portions of which are deflected upward and extend through the columns, and means for applying an upward thrust to the truss-rods. 50

In testimony whereof I have hereunto set 55 my hand in presence of two subscribing witnesses.

ROBERT W. JEMISON.
